Primary Examiner — Darlington Ly(74) *Attorney, Agent, or Firm* — Notaro, Michalos & Zaccaria P.C.(57) **CLAIM**

The ornamental design for a handheld heat iron, as shown and described.

DESCRIPTION

FIG. 1 is a top, right perspective view of a handheld heat iron showing my/our design therefor;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

Throughout the drawings the broken lines form no part of the design.

1 Claim, 7 Drawing Sheets(56)
